UNITED STATES PATENT OFFICE.

EDWARD J. McCUALEY, OF PHILADELPHIA, PENNSYLVANIA.

ROLLER-SUPPORTING DEVICE.

1,306,155.

Specification of Letters Patent. Patented June 10, 1919.

Application filed February 14, 1919. Serial No. 276,935.

To all whom it may concern:

Be it known that I, EDWARD J. McCUALEY, a citizen of the United States, residing at Philadelphia, in the county of Philadelphia 5 and State of Pennsylvania, have invented certain new and useful Improvements in Roller-Supporting Devices, of which the following is a specification.

One object of my invention is to provide 10 improved supporting devices for the re-rolling rollers for printing presses; it being well known that re-rolling rollers are employed to re-roll the form-rollers in order to provide an even distribution of the ink on said 15 form-rollers.

Prior to my invention various supporting devices have been employed for re-rolling rollers, but said devices were of such nature as to require constant manual adjustment to 20 prevent "dragging."

Another object of my invention is to so construct my improved supporting devices that the re-rolling rollers will always be held in proper relation to the form rollers; there- 25 by avoiding "dragging" and insuring an even distribution of the ink on said form-rollers.

Another object is to make my invention of a simple and durable construction and so as 30 to permit the quick and easy insertion and removal of the re-rolling rollers.

These objects, and other advantageous ends which will be described hereinafter, I attain in the following manner, reference 35 being had to the accompanying drawings in which—

Figure 1 is a side elevation showing a printing press form-roller carriage having my invention thereon,

40 Fig. 2 is a fragmentary section taken on the line 2—2 of Fig. 1.

Fig. 3 is a section of one of my improved supporting devices and taken on the line 3—3 of Fig. 1;

45 Fig. 4 is a section taken on the line 4—4 of Fig. 1 and

Fig. 5 is an inverted plan view of Fig. 1.

Referring to the drawings, 6 represents a 50 form-roller carriage having form-rollers 7, 8 and 9 mounted thereon in the usual man-

ner, and as clearly illustrated in Figs. 1 and 2.

My invention includes two brackets 10 and 11 which are similarly constructed; each of said brackets including a base plate 12 which is adapted to be secured to the opposite sides 55 of the frame 6 by machine screws 13. The sides of the frame 6 provide a convenient support for the brackets 10 and 11 since said sides of the frame 6 are usually made plane. 60

Each of the brackets 10 and 11 as illustrated in the drawings includes two boxes or casings 14 which are open at their opposite ends and on their outer side surface are provided with cover plates 15. Guide-ways 16 65 are thus provided in each of the boxes 14, said guide-ways being tapered or wedge shape in cross section as clearly shown in Fig. 2. A bar 17 slidably fits within the guide-ways 16 of each of the boxes 14 and 70 has a stem 18 which projects outside of the box. These stems 18 have collars 19 secured thereto adjacent their outer ends and rings 20 thereon adapted to abut the ends 21 of the respective boxes 14. Coiled springs 22 75 surround the stems 18 and are interposed between the respective collars 19 and rings 20. These springs 22 serve to move the bars 17 in the direction of the arrow α as shown in Figs. 1 and 3. The opposite ends of the bars 80 17 have heads 23 pivotally secured thereto by pivot pins 24. Thus the heads 23 can swing on the pivot pins 24 in a direction transversely to the axes of the form-rollers 7, 8 and 9. Each of the heads 23 has a notch 85 25 which extends in the direction of the length of the head; each of said notches having a mouth 26 which leads to the outer side surfaces 27 of the respective head 23.

The notches 25 form sockets for the opposite end terminals 28 and 29 of axles 30 which support the re-rolling rollers 31.

I preferably make each of the axles 30 of a piece of light weight metallic tubing 32 having end pieces 33 forced therein and secured by pins 34. Each re-rolling roller 31 is rotatably supported on the axle 30 as clearly shown in Fig. 4, said axle having collars 35 secured thereto within the rollers 31. The rollers 31 are preferably made of 100

light weight metallic tubing having bearing rings 36 and 37 forced within their opposite ends.

If desired these bearing rings can be soldered to the inner surface of the rollers 31. The collars 35, by being positioned within the rollers 31, prevent relative longitudinal movement between the axles 30 and the rollers 31.

10 In the use of my invention, the opposite end terminals of each of the re-rolling rollers are mounted within the notches 25 of two oppositely disposed heads 23; said heads as previously stated being respectively pivoted to two of the bars 17. The springs 22 serve to move the re-rolling rollers into engagement with two of the form-rollers in the manner clearly shown in Fig. 1. By having the heads 23 pivoted to the bars 17, opposite 15 portions of the re-rolling rollers will always engage the adjacent form-rollers since the heads 23 are capable of swinging in either direction. In other words, the action of the springs 22 is to pull one of the re-rolling rollers within the space between two of the form-rollers. However, the moving action of the springs 22 is arrested when the re-rolling roller engages the adjacent form-rollers. The tension of the springs 22 can 20 be varied by moving the collars 19 longitudinally upon the stems 18. Each of the collars 19 is provided with a set screw 38 which serves to adjustably secure the collar 19 to the respective stem 18. Therefore it is obvious that by the use of my invention it is 25 possible to keep the re-rolling rollers always in engagement with two adjacent form-rollers and that any desirable pressure of said re-rolling rollers upon said form-rollers can 30 be secured.

Each of the heads 23 at its outer end is provided with oppositely disposed projecting lips 39. These lips 39 can be easily grasped between the fingers when it is desired to remove one of the re-rolling rollers and, by pulling the heads against the actions of the springs 22, the re-rolling rollers can 45 be moved sufficiently far away from the form-rollers to permit the end terminals 28 and 29 to be lifted from the notches 25 through the mouths or openings 26. Therefore no tools are required either to remove 50 or replace the re-rolling rollers.

By constructing the brackets 10 and 11 as 55 above described they can be attached to any form of printing press form-roller carriage merely by screwing the brackets to the frame of the carriage as by the screws 13. It is therefore unnecessary to alter or change the 60 construction of a form-roller carriage in order to attach my invention thereto and for this reason also, my invention is of particular value.

While I have described my invention as taking a particular form, it will be understood that the various parts of my invention may be changed without departing from the spirit thereof, and hence I do not limit myself to the precise construction set forth, but consider that I am at liberty to make such 70 changes and alterations as fairly come within the scope of the appended claims.

Having thus described my invention, what I claim as new and desire to secure by Letters Patent is:

75 1. The combination with a printing press having a form-carriage and form inking rollers mounted on said carriage; of two spring-pressed bars slidably supported on said form-carriage; members swingably connected to said spring-pressed bars; and an ink distributing roller rotatably supported in said swingably connected members whereby said ink distributing roller is pulled into contact with two adjacent form inking rollers; substantially as described.

80 2. The combination with a printing press having a form-carriage and form inking rollers mounted on said carriage; of two spring-pressed bars slidably supported on said form-carriage; members swingably connected to said spring-pressed bars; and an ink distributing roller rotatably supported in said swingably connected members whereby said ink distributing roller is pulled into 90 contact with two adjacent form inking rollers, said spring-pressed bars being movable in paths extending between said two form inking rollers, substantially as described.

85 3. The combination with a printing press having a form-carriage and form inking rollers mounted on said carriage; of two spring-pressed bars slidably supported on said form-carriage; members swingably connected to said spring-pressed bars; and an ink distributing roller rotatably supported in said swingably connected members whereby said ink distributing roller is pulled into contact with two adjacent form inking rollers; said swingably connected members having notches therein providing openings at the sides thereof and adapted to receive the bearing portions of said ink distributing roller, whereby said latter roller can be quickly detached after said swingably connected members have been pulled to free said ink distributing roller from said form-rollers; substantially as described.

95 4. A device of the character described including a bracket having a box provided with a passageway, a member slidably mounted in said passageway, a spring adapted to slide said bar in one direction within said passageway, a head pivotally connected to said bar and adapted to be 100 moved toward the bracket due to the action

of said spring, said head being operative to support the end of a roller; said box including a removable cover plate adapted to cover the length of said passageway where-
5 by when the cover is removed the bar can be lifted bodily from said passageway; sub-stantially as described.

In testimony whereof I have signed my name to this specification in the presence of two subscribing witnesses.

EDWARD J. McCUALEY.
